ROLL TAPE CONTAINER

Sanford J. Ellenburg, Berkeley, Calif., assignor
to Handy-Roll Company, Oakland, Calif., a
corporation of California

Application August 22, 1934, Serial No. 740,913

4 Claims. (Cl. 242—55.4)

This invention relates to adhesive and other roll tape containers from which such tapes are projected as desired for use, and the objects of the invention are to provide improvements in such containers whereby a variety of and/or widths of tapes and other adhesive devices may be instantly presented for use, to thereby avoid the present requirement of keeping on hand several containers and the great loss of time in changing 5 from one to the other as the work of repairing a lot of file papers, manuscripts or the like, is undertaken.

In the drawing Fig. 1 is a perspective view of my improved device as seen from the front end. 15 Fig. 2 is a plan view with the upper wall omitted to show the arrangement of adhesive or other papers or strips within.

Fig. 3 is a longitudinal section of Fig. 2 as seen from the line 3—3 of Fig. 2.

With further reference to the drawing the device comprises a container preferably made of thin sheet metal taking the general form of a pointed heart when seen in plan as in Fig. 2 and comprising a top wall 1, bottom 2, and side walls 3 which terminate in a slot 17 at the apex of the heart. These walls are permanently secured together (after filling the container) as by soldering, crimping, or the use of small ears 4 from one part projecting through small slots 20 in the adjacent part and bent over, and within the forward part of the container or converging sides is a pair of extra curved walls or guides 5 firmly secured in place. These extra walls are spaced slightly from the outer walls of the container so as to form slight channels through 25 which the gummed tape is drawn, are joined at their forward ends to form an apex 6 extending within the slot formed by the side walls, and at their rearward ends are curved inwardly as at 30 7 to readily guide strips of paper or other material respectively from rolls 8, 9 arranged within the container, through the channels or guides and out of the apex of the device as at 8' and 9'.

As one of the objects is to provide a container 45 which will dispense various widths of tapes, roll 8 is shown full width of the container height, while roll 9 is only about half width, also the materials of the rolls may be of different kinds, the wide one say as of cloth or opaque paper, 50 and the narrow one of transparent or translucent pellicle, so that they may be used, the first, say on back of a torn piece of printed matter or manuscript, and the second, over the same tear but on the face of the sheet. To keep the narrow roll in best position for unrolling I may pro-

vide a partition 18 to support the narrow roll and a wall 11 to separate both rolls. The rolls of tape may, if desired, be of different sizes or lengths, as well as of different quality or kind, if desired, gummed or plain, also with or without 5 printing.

To further adapt the container to the work of repairing and/or binding file documents, I provide a supply of gummed eyelets 12 in a tube 13 positioned forward of the tape rolls 8 and 9 and 10 between the curved guide walls 5. These eyelets 12 are of paper, cloth or the like, and are resiliently forced outwardly by a light coiled spring 14 to stop against an inwardly turned marginal flange 15 at the outer open end of the tube, and 15 which flange extends but about two-thirds around the edge of the tube so as to have a free space toward the forward edge of the container and through which space the eyelets may be slipped out one at a time with the finger.

The opposite side walls 3 are each formed with a finger slot 16 through which the tapes may be urged outward through the slot 17 at the apex of the container, and to facilitate withdrawing of the tapes by contact with the tip of the finger, 20 walls 5 are each provided with an elongated flat boss 5', which are positioned close to walls 3 and within the outline of slots 16, and against which bosses the tapes are pressed with the finger and then moved forward. After drawing out the 25 desired length it is torn off against one of the side walls which is left with a sharp corner for this purpose.

The elongated boss 5' makes it much easier 30 to slide the tape out with the finger as it permits of a large free space for guiding the tape yet keeps the finger contact elevated close to the outer wall of the container and thereby also avoids danger of cutting the finger on the edges of the slot 16.

Having thus described my invention, what I 35 claim is:—

1. A roll tape package comprising a box formed at one side with an apex with a slot in the apex, a plurality of separate rolls of tape in said box 45 with the free ends of the tapes extending out of the apex, and means within the box guiding the tapes to said apex for dispensing therefrom and arranged to maintain the tapes separated substantially to the point of emergence. 50

2. A roll tape package comprising a box formed at one side with an apex with a slot in the apex, a plurality of separate rolls of tape in said box with the free ends of the tapes extending out of the apex, means within the box guiding the tapes 55

separately to said apex for dispensing therefrom, the rolls of tape within the box being of dissimilar width with the widest substantially equal to the space between the walls of the box, and a 5 partition in the box supporting the narrower roll of tape in position.

3. A roll tape package comprising a box substantially of heart shape when viewed in plan and formed with an apex at the small end of the 10 heart with a slot in the apex, a plurality of separate rolls of tape in said box with the free ends of the tapes extending out of the apex, means within the box guiding the tapes separately to said apex for dispensing therefrom, and said box 15 provided with finger slots in opposite sides adjacent said apex.

4. A device for dispensing tape comprising a sheet metal container adapted to hold a roll of tape and having a slot through which the tape extends, a finger slot in the side wall of the container to expose the tape for movement by the finger, a guiding wall within the container under the finger slot guiding the tape close to said side wall, said guiding wall provided with an outwardly raised boss aligned with but of smaller area than said finger slot and falling within the 10 outline of the slot and against which boss the tape is pressed by the finger when moving the tape, all so that the finger will be kept substantially out of the slot when moving the tape. 15
